UNITED STATES PATENT OFFICE.

ALLAN GORDON SMITH, OF LONDON, ENGLAND, ASSIGNOR TO S. SMITH & SONS (MOTOR ACCESSORIES) LIMITED, OF LONDON, ENGLAND.

DESIGN FOR AN INSTRUMENT-BOARD PANEL.

Application filed June 22, 1926, Serial No. 18,187, and in Great Britain May 14, 1926. Term of patent 7 years.

To all whom it may concern:

Be it known that I, ALLAN GORDON SMITH, a subject of the King of England, residing at Cricklewood Works, Cricklewood, London, England, have invented a new, original, and ornamental Design for an Instrument-Board Panel, of which the following is a specification, reference being had to the ac-

companying drawing, forming part thereof.

Figure 1 is a plan view of the article showing my new design and Figure 2 is an end elevation thereof.

I claim:

The ornamental design for an instrument board panel as shown.

ALLAN GORDON SMITH.
